UNITED STATES PATENT OFFICE.

ALBERT H. LEWIS, OF LOS ANGELES, CALIFORNIA.

GAME.

1,242,002.

Specification of Letters Patent.

Patented Oct. 2, 1917.

Application filed February 15, 1917. Serial No. 148,728.

To all whom it may concern:

Be it known that I, ALBERT H. LEWIS, a citizen of the United States, residing at Los Angeles, in the county of Los Angeles and State of California, have invented new and useful Improvements in Games, of which the following is a specification.

It is an object of this invention to provide a game which will hold the attention 10 of and amuse the players, require the exercise of their mathematical skill, and is suggestive of the savings habit.

The invention resides primarily in a board having a group of columns consisting 15 of spaces representing savings of various denominations of money and a deposit space; with the board, dice are used to indicate by throws the amounts saved, such amounts being indicated on the rows of 20 markers.

An embodiment of my invention is illustrated in the accompanying drawing, in which:

Figure 1 is a plan view of the game board. 25 Fig. 2 shows a dice box and dice to be used in playing the game, and

Fig. 3 markers which are used upon the board.

A indicates a board made of card-board, 30 or other suitable material, which may be divided through the center so that it may be folded for the convenience of storing. Upon the board are four players' fields, B, C, D, and E, which may be distinguished 35 by coloring each field differently. Such coloring will also increase the attractiveness of the board. Each field is identical in its markings, and one only will be described, as this will suffice to illustrate the marking 40 on the other fields.

Extending diagonally across the field C is a column F of spaces or rectangles indicating cents. Extending along one edge of the field is a column G indicating dimes, and 45 along another edge intersecting G and F at the center of the board, is a column H indicating nickels. A triangular space J at the inner corner of the field C forms one fourth part of a square, the other portions 50 being similar triangles in the other fields. The space J is marked "\$5.00 saved." The adjacent space on the nickel column is marked "Bank." The space on the dime column adjacent to the triangle J is also marked "Bank." The column F has markings 55 from one to nine cents. The 8 cent

space is marked "Spent," while the other spaces in the row are marked "Saved." In the nickel row, indicated by H, the five cent space is marked "Spent," while the remaining spaces are marked "Saved." All the spaces in the ten cent row are marked "Saved." The five cent space and the eight cent space may conveniently be indicated by coloring the spaces differently from the other spaces in the row.

Each player should be provided with a set of markers. The set will include one marker designating one cent, 5 markers each designating a nickel, and marked five 70 cents, and 5 each designating a dime marked 10 cents. The 11 markers of each set are preferably differently colored to distinguish the sets. A marker of each denomination is shown in Fig. 3.

Two dice of the usual type and having markers from 1 to 6 constitute a necessary part of the game. As the dice are to be thrown, it is convenient to use a dice box.

The board shown is intended to accommodate four players, but a less number may play if desired. For convenience, each player should be provided with two dice and a dice box. Each player is entitled to two throws of the dice in turn. The spots on 80 each dice face up added together indicate the number of cents saved and must first be applied toward saving the nickels. In starting the game if a player makes a throw which amounts to less than 10 cents, only 90 the amount over 5 cents or a nickel may be marked up in the cents column as saved. The first nickel is spent and does not count. If less than five is thrown the first time such number is counted in the cents column. 95 If, on the second throw, the spots face up added to those in the cents column give ten or more, a marker may be started in the nickel column on the ten cent space, any remaining cents to be added or used at the 100 player's next turn to throw. The remaining cents are indicated by the markers in the cents column.

The amount in the nickel column and any amount in the cents column are forfeited 105 if a throw is made which, added to any cents marked up in the cents column, makes an even eight cents. Thus, if there are three cents marked up in the cents column and five is thrown with the dice, this will make eight. 110 The markers are then removed from both the cents column and the nickel column, both

the nickels and dimes saved being "spent" or forfeited. After a nickel reaches the fifty cent space, an additional throw of five is necessary to deposit the same in the "bank," 5 where it cannot be spent or forfeited. A player must deposit all of his nickels in the "bank" first and then start upon the dimes.

A player has the privilege of entering another nickel in the nickel column before 10 moving the preceding one into the "bank," if his throw is sufficient to allow it. If the player starts the second nickel and then makes a throw so that he stops upon the eight cent space in the cents column, he will 15 forfeit both the markers in the nickel column losing all he has "saved."

When a throw produces an amount which is to be added to the cents column, the result being equal to or greater than five, five 20 cents is added in the nickel column and the surplus marked up in the cents column.

After all the nickels have been deposited in the "bank," the dimes are saved. The dimes are also subject to forfeiture or being 25 spent when the cent marker stops at eight cents. The play with the dimes is similar to that with the nickels, but there is no first dime "spent." The player who succeeds first in saving \$5.00 wins the game.

30 The game may be played by using only one player's field. The markers of each player being of different colors, the same columns may be used. The columns may also be arranged differently than that shown 35 in the player's field. It is merely essential that there be a bank deposit space and columns one for each denomination of money saved. A further variation of the invention, and which is included within the scope 40 of the claims, is that of a device equivalent to the dice. Any device which may be manually actuated and which will by chance indicate a number may be used instead of the dice.

45 What I claim is:

1. In a game, a board provided with the representation of a group of columns and a deposit space, each column being divided

and having indicia to indicate the divisions, said indicia increasing in arithmetical progression from one end of the column to the other, the difference in each column being that of a denomination of money; a plurality of sets of markers, each set comprising markers provided with indicia to represent the several denominations of money indicated on the columns; and means having indicia marked thereon in units of the lowest of said denominations, said means being manually actuatable to indicate by chance 60 numbers.

2. In a game, a board provided with a representation of columns radiating from a deposit space, each column being divided into spaces marked with indicia decreasing 65 in arithmetical progression from the deposit space, the difference in each column being that of a denomination of money; a plurality of sets of markers, each set comprising markers provided with indicia to 70 represent the several denominations of money indicated on the spaces; and means having indicia marked thereon in units of the lowest of said denominations, said means being manually actuatable to indicate by 75 chance numbers.

3. In a game, a board provided with a representation of a deposit space, sets of three columns radiating therefrom, one column having spaces therein marked with indicia decreasing in differences of one cent from the deposit space, the second row having spaces therein marked with indicia decreasing in differences of a nickel from the deposit space and the third column having 85 spaces marked with indicia decreasing in differences of a dime from the deposit space; a plurality of sets of markers comprising one marked a cent, another marked a nickel and a third marked a dime; and means including a die to indicate by chance numbers 90 in units of one cent.

In witness that I claim the foregoing I have hereunto subscribed my name this 3rd day of February, 1917.

ALBERT H. LEWIS.
